UNITED STATES PATENT OFFICE.

SAMUEL M. RHOADS, OF JEFFERSONVILLE, PENNSYLVANIA.

THILL-COUPING.

SPECIFICATION forming part of Letters Patent No. 225,867, dated March 23, 1880.

Application filed January 30, 1880.

To all whom it may concern:

Be it known that I, SAMUEL M. RHOADS, of Jeffersonville, in the county of Montgomery and State of Pennsylvania, have invented a new and Improved Shaft or Pole Coupling, of which the following is a specification.

Figure 1 is a sectional side elevation with the shaft attached. Fig. 2 is a sectional front elevation of the coupling on line *x x*, Fig. 1. Fig. 3 is a plan view, showing the method of securing the thumb-screw strap to the under side of the shaft or pole. Fig. 4 is a plan of the cover of the coupling. Fig. 5 is a perspective of the lower part of the coupling.

Similar letters of reference indicate corresponding parts.

The object of this invention is to provide a simple and durable shaft or pole coupling for vehicles.

The invention consists in combining with the cushion of a thill-coupling a box having a recess and back piece, a separate axle-clip, a screw-threaded cap having ears that clasp the box, cut-away ears, and nut, as hereinafter fully described.

In the drawings, A represents the box or lower part of the coupling, held to the axle B by the clip C, and projecting in front of the said axle B, as shown. The two sides of the box A have semicircular notches *a a* made in their upper edges, in which notches rests the bolt D, that passes through the eye *b* of the shaft or pole E. In the front of the box A is formed a rectangular socket or depression, *c*, which supports the rear end of the shaft or pole E and prevents the lateral movement thereof. The cap or cover F of the box has a flat top, cut away so as to form rearward-projecting ears *d d*, which clasp both sides of the upward-extending back piece *f* of the box; and this cover or cap F has also two forward-projecting ears, *g g*, which assist in preventing the lateral movement of the shaft or pole of the vehicle, and these ears *g g* are cut away on the under side, as shown at *s*, so that the said cover or top F may fit more closely and securely in its seat on the box A.

Projecting downward at right angles from the cover F is its shank G, having vertical sides and back and a curved or recessed front, 50 as shown at *h*, Fig. 1. This shank G is prolonged into a screw, which extends down through a hole, *m*, in the bottom of the box A, and on the end of this screw is turned the thumb-nut H, to hold the said cover F in 55 place. Within the recess formed by the shank and top of the cover F is placed an elastic buffer or cushion, I, which presses upon the eye *b* of the shaft or pole E when the said cover F is screwed down into place. At 60 attached to this thumb-nut H, and made a part of it, is the loop *n*, and the said thumb-nut H is prevented from accidentally turning, and thus becoming loose, by the strap K, whose one end is secured in the loop *n*, while the 65 other end of said strap K is buttoned on the button *o* and passed through the loop *p* of the plate L, which is fastened on the under side of the shaft or pole E.

It will be seen that by simply unscrewing 70 the thumb-nut H the cover F may be readily lifted and the shaft or pole with its bolt be removed from the box; and it is obvious, also, that a shaft or pole may be held firmly in position by this coupling, and without rattling, though having sufficient play, when the elastic-lined cover is drawn tightly down upon it.

Having thus described my invention, I claim as new and desire to secure by Letters 80 Patent—

In a thill-coupling, the combination, with the cushion I, of the box having rectangular recess *c* and back piece, *f*, of the separate axle-clip, the screw-shanked cap F G, having ears 85 *d g*, and the nut H, the ears *g* being cut away at *s*, as shown and described.

SAMUEL MARKLEY RHOADS.
